UNITED STATES PATENT OFFICE.

RAYMOND W. BURDSALL, OF GLOUCESTER HEIGHTS, NEW JERSEY.

SIGNAL APPARATUS.

Application filed November 17, 1923. Serial No. 675,352.

One object of my said invention is the provision of a signal apparatus adapted when actuated to attract the attention of a deaf person and thereby apprise such person 5 of the fact that a caller is at the door.

Another object of the invention is the provision of a signal apparatus adapted by a bouncing of a ball and vibratory action caused thereby to attract the attention of a 10 deaf person and at the same time to cause a signal lamp to glow and a buzzer to sound, the sounding of the buzzer serving to attract the attention of persons who are not deaf and who might be in an apartment 15 adjacent to that in which the apparatus is arranged.

To the attainment of the foregoing, the invention consists in the improvement as hereinafter described and definitely claimed.

20 In the accompanying drawings, forming part of this specification:—

Figure 1 is a view partly in elevation and partly in section of the apparatus constituting the preferred embodiment of my invention.

25 Figure 2 is a diagrammatic view illustrative of the electrical wiring comprised in the apparatus.

Similar numerals designate corresponding 30 parts in both views of the drawings.

Among other elements my novel apparatus comprises a casing body 1. The said casing body 1 is provided with a door 2, and may be of the construction illustrated 35 or of any other construction compatible with the purpose of my invention.

Fulcrumed at 3 in the casing body 1 is a platform lever 4 which extends through an opening in one wall of the casing body 1 40 and is provided in its portion exterior of the casing body 1 with a depression 5. The said depression 5 is adapted to seat a displaceable ball 6 which may be and preferably is of medium hard rubber so that 45 when it is precipitated to the floor it will bounce and give rise to a vibratory action calculated to attract the attention of a deaf person. At this point, I desire it distinctly understood that while I prefer to employ a 50 rubber ball of medium hardness, the ball 6 may be a ball of any other description appropriate to its indicated purpose. On the inner arm of the platform lever 4 is provided a contact strip 7 for cooperation with 55 terminals 8 arranged in a normally open circuit with a source of electric energy and

an incandescent lamp 9 whereby when the platform lever 4 is released as hereinafter described and is swung by the gravitation of its comparatively heavy outer arm, the 60 circuit mentioned will be closed so as to bring about the glowing of the lamp 9, which glowing will continue and afford a visible signal until the apparatus is reset by the lowering of the inner arm of the platform lever 4 and the placing of the 65 said platform lever 4 in engagement with the catch 10 on an armature 11. The said armature 11 is preferably constructed and equipped as illustrated and is opposed to 70 electro-magnets 12 whereby when the electro-magnets are energized the armature will be caused to oscillate and thereby give rise to a buzzing sound calculated to attract the 75 attention of a person with good hearing notwithstanding such person might be in an apartment adjacent to that containing my novel apparatus. In this connection it will be understood that the initial movement of the armature 11 toward the magnets 12 will 80 bring about the mentioned release of the platform lever 4 with the result that the contact plate on said lever 4 will effect electric connection between the terminals 8 so that the lamp 9 will be caused to glow 85 until the apparatus is reset, and this notwithstanding the fact that the buzzing action will cease when the circuit containing the magnets 12 is opened.

Any appropriate means may be employed 90 for closing the circuit containing the magnets 12 though I prefer to employ for the purpose an ordinary or any other approved push button 13 which is designed to be arranged exterior of a dwelling and adjacent 95 to the entrance thereof.

Manifestly when the apparatus is set as 100 illustrated in Figure 1 and the push button is pressed, the magnets will be energized, and such energization will be attended first 105 by the movement of the armature 11 out of engagement with the platform lever 4 to release the latter and to precipitate the ball 6 to the floor and to bring about the glowing 110 of the incandescent lamp 9. Said initial action will be followed by the described oscillation of the armature 11 for the purpose of affording the buzzing sound or audible signal before mentioned. When pressure is removed from the push button 13, the electro-magnets 12 will be deenergized and the buzzing sound will cease, but the

glowing of the incandescent lamp 9 will continue until the apparatus is manually reset by the drawing down of the inner arm of the platform lever 4, and the placing of the end of said arm under the catch 10 of the armature 11 as shown in Figure 1. When the door 2 of the casing body 1 is opened access manifestly may be readily gained to the inner arm of the platform lever 4 for the downward movement of said arm, or if preferred the apparatus may be reset by the application of the hand to the outer arm of the platform lever, and this without opening of the door 2. After the platform lever is replaced in engagement with the armature 11 as stated the setting of the apparatus is completed by the manual placing of the ball 6 in the depression 5.

As clearly shown in Figure 1, I prefer to employ in the apparatus an appropriate switch 14 through the medium of which the circuit may be opened when desired. This, however, is not of the essence of my invention and it will therefore be understood that the switch 14 may be employed or may be altogether omitted without affecting my invention as defined in my appended claims. I would also have it understood that as shown the apparatus comprises a transformer 15 so that the apparatus may be connected with the electric wiring of a dwelling. This, however, is also not of the essence of my invention, and it will, therefore, be understood that the terminals or binding posts 16 may be connected with any suitable source of electric energy without affecting my invention.

It will be apparent from the foregoing that notwithstanding the simplicity of my improved apparatus, the same may be depended upon to put on notice a deaf person when a caller actuates the push button 13, the closing of the circuit by the manipulation of a push button 13 bringing about the release of the platform lever 4 and the precipitation of the ball 6 coincident with or followed closely by the closure of the lamp

circuit with the result that the lamp will be continued to glow. Then so long as the push button 13 is subjected to pressure and the armature 11 is oscillated, a buzzing sound will be afforded adapted to attract the attention of such persons in the vicinity of the apparatus as are able to hear. The buzzing sound will be afforded so long as the push button 13 is subjected to pressure, but when the push button is released of pressure the buzzing will be caused to cease, though the lamp 9 will continue to glow as before described until the apparatus is reset.

I have entered into a detailed description of the construction and relative arrangement of the parts embraced in the present and preferred embodiment of my invention in order to impart a full, clear and exact understanding of the said embodiment. I do not desire, however, to be understood as confining myself to the specific construction and relative arrangement of parts inasmuch as in the future practice of the invention various changes and modifications may be made such as fall within the scope of my invention as defined in my appended claim.

Having described my invention, what I claim and desire to secure by Letters Patent, is:—

A signal apparatus adapted to attract a deaf person and comprising a casing, a platform lever pivoted within the casing to swing in a vertical plane and having a depressed portion extending exteriorly of the casing, a ball adapted to normally lie on the depressed portion of said platform lever, means for normally retaining said platform lever in a horizontal position, and magnetic means for releasing said first mentioned means so that the weight of the ball will move the lever on its pivot to drop said ball whereby the latter will bounce to attract the deaf person.

In testimony whereof I affix my signature.

RAYMOND W. BURDSALL.
